CLAIM

The ornamental design for a housing for an electronic bar code reader, as shown and described.

DESCRIPTION

FIG. 1 is a front perspective view of a housing for an electronic bar code reader showing our new design;

FIG. 2 is a front elevational view thereof;

FIG. 3 is a right side elevation view thereof;

FIG. 4 is a rear elevational view thereof;

FIG. 5 is a top plan view thereof;

FIG. 6 is a bottom plan view thereof;

FIG. 7 is a front perspective view of a second embodiment of our new design;

FIG. 8 is a front elevational view thereof;

FIG. 9 is a top plan view thereof;

The undisclosed views of the second embodiment are similar to those of the first embodiment.

FIG. 2.

FIG. 7.

FIG. 9.
